US0D1038105S

(12) **United States Design Patent** (10) Patent No.: **US D1,038,105 S**
(45) Date of Patent: ** Aug. 6, 2024

(54) **RING HOLDER**

(71) Applicant: **SPIGEN KOREA CO., LTD.**, Seoul (KR)

(72) Inventors: **Bonyoung Koo**, Seoul (KR); **Jin Yong Choi**, Seoul (KR); **Eun Mi Kim**, Seoul (KR)

(73) Assignee: **SPIGEN KOREA CO., LTD.**, Seoul (KR)

(**) Term: **15 Years**

(21) Appl. No.: **29/864,825**

(22) Filed: **Jun. 23, 2022**

(51) LOC (14) Cl. **14-03**

(52) U.S. Cl.

USPC **D14/253**; D3/218

CLAIM

The ornamental design for a ring holder, as shown and described.

DESCRIPTION

FIG. 1 is a front perspective view of the ring holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the ring holder that form no part of the claimed design.

1 Claim, 7 Drawing Sheets
